UNITED STATES PATENT OFFICE.

WILLIAM H. JOHNSON, OF BRANDON, VERMONT.

MACHINE FOR PRINTING PENCILS.

No. 910,289.

Specification of Letters Patent.

Patented Jan. 19, 1909.

Application filed July 15, 1908. Serial No. 443,715.

To all whom it may concern:

Be it known that I, WILLIAM H. JOHNSON, a citizen of the United States of America, and resident of Brandon, in the county of 5 Rutland and State of Vermont, have invented certain new and useful Improvements in Machines for Printing Pencils, of which the following is a full, clear, and exact description.

10 This invention relates to printing and embossing machines, and more particularly to that class thereof in which certain characters may be impressed or rolled into cylindrical bodies of various kinds, such as for instance 15 pencils, package handles, pill boxes, etc., and it has for one of its objects the provision of a machine in which the articles to be marked are contained in a hopper or reservoir from which they gravitatively descend 20 into the impressing mechanism, and are subsequently automatically discharged.

My invention has, furthermore, for its object the provision of improved impression devices which comprise flat surfaces between 25 which the articles are rolled along and into engagement with a suitable die or type form.

A further object of the invention resides in the improved construction of the inking mechanism whereby ink, bronze or similar 30 material may be deposited onto the dye or type.

Further objects of the invention will hereinafter appear, and the means for their attainment be particularized in the claims.

35 In the accompanying drawings, in which similar characters denote similar parts,— Figure 1 is a side view of a machine embodying my invention; Fig. 2 is a top view thereof; Fig. 3 illustrates a vertical section on line 3—3, of Fig. 1, and Fig. 4 shows a longitudinal section on line 4—4, of Fig. 2, as seen in direction of arrow. Figs. 5 and 6 are cross sectional views on lines 5—5, and 6—6, Fig. 2.

45 Briefly stated, the machine comprises a vertically-disposed reservoir in which the articles to be marked are supported one above the other, and from which they descend one by one onto a receiving bed which 50 contains the marking die. This die may be supplied with ink, bronze or similar material, and the article is forcibly rolled over said die and subsequently dropped through an aperture in the bed; while another blank 55 article will be permitted to leave the reservoir and enter the machine, as before.

In the drawings, 10 denotes the bed of the machine supported on legs 11 and having at its rear side bearing brackets 12 in which the main shaft 13 of the machine is journaled. Rotary movement is imparted to this shaft by a clutch pulley 14 which is normally loose thereon but may be operatively connected therewith by a cone-spool 15 operable by a hand lever 16, which is fulcrumed 60 at 17.

The shaft 13 actuates in properly timed manner a pair of mechanisms, viz.: one for bringing successive blanks into contact with the impression-device, and the other for supplying this device with ink or other suitable marking material. In the present case the machine is adapted to impress lettering upon the cylindrical surface of pencils, which are placed into a reservoir or hopper H formed 70 of a pair of trough-like members 20 provided with guide strips 21 between which the pencil-blanks P are held endwise. Each pencil, as it issues from between the strips 21, drops into the flat-surface bed 10 (see 80 Figs. 3 and 4) which is provided with a pocket 22 to receive a die or type form 23 which may be vertically adjusted as for instance by a thumb-screw 24 and held by a screw 25. The blank is rolled along the 85 bed 10 by a pressure-slide or platen 26 having a flat under-face and reciprocable in ways 27 of the bed, by an ear-bolt 28 attached to said slide and connected through a link 29 with a lever 30, which is pivoted at 90 31 and carries a roller 32 acted upon by a cam 33. This cam is secured to a cross-shaft 34, journaled in bearings 35, and having at one end a bevel gear 36 engaged by a pinion 37 on the shaft 13 above mentioned. 95

Referring to Fig. 4, it will be seen that the slide 26 is active in rolling a pencil P' over the type form the cam 33 not yet having attained its limit of throw-movement, so that, as the shaft 34 is rotated in the direction 100 of arrow a, said slide will ultimately bring the pencil P' into position to drop through an aperture or slot 38 in the bed plate. Means are provided for permitting a new blank to drop into position to be rolled by 105 the slide 26, these means being preferably controlled by the movement of the slide and connected with the hopper H in such a manner that only one blank will be fed at a time. This mechanism comprises what may be 110 termed a "by-pass" slide, consisting of a separating or check member 40, and a holder

or shelf 41, which latter is made in the shape of a yoke (see Fig. 2) and supports said member 40. The yoke is mounted for short sliding movement on extensions 42 secured 5 to the hopper H, and it is actuated in one direction (from left to right in Fig. 4) by an adjustable abutment screw 43 (carried by a lug on the rolling-slide 26) engaging an abutment 44 secured to the underside of said 10 yoke. As soon as this engagement takes place, the yoke is moved bodily toward the right as Fig. 4 is viewed, thus bringing the shelf 41 beneath the stack of pencils in the hopper, and at the same time withdrawing 15 the separator 40 from below the lowermost blank in the hopper, so that this blank can now fall onto the shelf and into such position that the separator in its return stroke 20 can pass below and hold the next blank in the hopper.

Inasmuch as the blanks in the hopper and above the shelf 41 can move only vertically by virtue of the confinement of their ends in the channel bars 20, it follows that a 25 pencil on the shelf 41 will drop only after said shelf has been withdrawn from beneath it, this action being accomplished subsequently to or during the return movement of the rolling-slide 26, and by the second 30 mechanism controlled by the main shaft 13 above stated. This second mechanism, viz.: the ink-supplying device for the die or type form 23, consists of a carriage 50 connected by a link 51 with a lever 52 which is fulcrumed at 53 and carries a roller 54 engaged by a cam 55 on a cross-shaft 56, which has a bevel gear 57 (see Figs. 1 and 3) and is journaled in bearings 58 of the frame. The gear 57 is in engagement with a pinion 35 59 on the main shaft 13, and the two mechanisms above described are so timed relatively to each other that they alternately cooperate with the type form 23. It should be noted that the cams 33 and 55 actuate 40 their respective levers 30 and 52 inwardly only, while a spring 60 interposed between a collar 61 on a tubular rod 62, and a collar 63 fixed on an inner rod 64, serve to hold both levers in engagement with the cams, as 45 50 will be readily understood.

The slide 50 carries a pair of composition rollers 65, 66, which take ink from a disk 67 rotatably mounted in a bearing 68 and on a center-screw 69 whereby said disk may be 55 vertically adjusted relatively to the rollers 65, 66. The disk is secured to a vertical shaft 70 which also carries a ratchet 71 which is intermittently rotated by a spring-retracted plunger rod 72 provided with a 60 pawl 73 and pushed inward by a pin 74 on the lever 52 during the final inward movement thereof.

The carriage 50 carries at one side a pin 75 adapted to engage a cam faced lever 76 65 which is pivoted at 77 and has an adjustable

abutment screw 78 for pushing the by-pass yoke with the shelf 41 and detent 40 so as to permit a blank to drop from the pile in the hopper, said screw engaging an abutment 79 in the yoke. 70

Inasmuch as the underside of the slide 26 is apt to be daubed with ink deposited on the blank by the die 23, I have provided a device whereby this ink will be wiped off from the slide, this device being preferably 75 a roller 80 covered with felt or some absorbent material, and journaled in an arm or frame 81 pivotally hung on shaft 84, which is adapted to yield to downward pressure by virtue of a spring 82 the compression of 80 which may be varied by a nut 83 on a stationary rod 84, the latter also having a fixed collar 85 which serves as a stop to limit the upward movement of said arm.

The roller 80 is rotated by the meshing 85 with a gear 91 thereon of a gear 86 on a stud shaft 87 also journaled in the arm 81 and having a pulley 88 which may be driven by a belt 89 from a pulley 90 secured on the shaft 34 above described. 90

The pencil rolling slide, or platen 26, is made with a portion which comprises its face that rolls over and upon the pencils yieldable so that variations in the diameters of pencils may be provided for; and 95 the construction to this end is particularly represented in the enlarged cross section Fig. 5, in which the platen is shown as constituted of upper and lower sections 93 and 94, the upper one having the side ribs which 100 engage in the aforementioned groove ways 27 in opposite sides of the frame. The upper section 93 has spring receiving sockets 95 concentrically within which are the 105 upstanding studs 96 unitary with the lower section 94 which are surrounded by the springs in compression between the top of the platen section 94 and the shoulders 97 at the upper ends of the spring sockets.

The screws 98 which have their heads in 110 countersunk sockets therefor alined with the spring sockets 95 have their shanks passed through holes therefor of reduced diameter and axially into the upstanding studs 96, so that to all intents and purposes, except as 115 regards practicability of assemblage the studs and headed screws are as integral parts.

The lower platen section is fitted in a broad, shallow, inverted, groove or recess, 120 therefor in the upper section, with sufficient clearance for receding in an upward direction to widen the space between it and the top of the bed 10 as, in its operation over the tops of pencils, may be required. 125

The carriage 50 which carries the inking rolls 65 and 66 is peculiarly constructed and operable so that the body of the carriage and its rollers may yield and accommodate themselves to inequalities in the surfaces or 130

kind of the ink supplying disks 67 and the type form 23. And as seen in the enlarged cross section Fig. 6, the body 102 of the carriage on which the inking rolls are carried is made separately from and spring supported from the bar 101 which engages through slots 103 in the side cheeks of the carriage, said bars by their outward extremities being provided with rollers 104 which have running engagements in the aforementioned side grooves 27 whereby the bar or rider 101 while freely sliding lengthwise of the machine is always maintained at a fixed level. A pair of rods 105 by their 15 eye formed lower ends embrace the rider bar 101 and upwardly project through holes therefor in the carriage above the top of the carriage receiving at their pressure extremities the spiral springs 107 which are held in 20 compression by the nuts 108.

The tendency of the springs is to force the carriage downwardly relatively to the rider bar and until resisted by whatever surface the carriage sustained inking rolls 25 may be running upon, whether it be the ink supply disk, the machine bed or the type form, and the yielding upwardly as accommodated by the slots 103 is against, and increases the compression of, the springs.

30 I claim:—

1. The combination with blank holding means and marking means, of a blank carrying device and inking mechanism coöperating with the marking means, and blank delivery means operated in one direction by the blank carrying device and in an opposite direction by the inking mechanism.

2. The combination with blank holding means and marking means, of a reciprocating blank carrying device and reciprocating inking mechanism alternately coöperating with the marking means, and blank delivering means including elements located in the path of movement of and operated alternately by the blank carrying device and inking mechanism.

3. The combination with a supporting table, of a marking device, blank moving means and inking mechanism operating from opposite ends of the table over the marking device, and blank feeding means actuated alternately by the moving means and inking mechanism.

4. The combination with a supporting table, of a stationary marking device mounted thereon, a blank holder arranged above and at one side of the marking device, a reciprocating platen sliding between the blank holder and marking device, separate reciprocating inking mechanism movable over the marking device, means for effecting the alternate movement of the platen and inking mechanism, and feed controlling means actuated alternately by the platen and inking mechanism.

5. The combination with a marking device, of a platen and inking mechanism alternately movable over the marking device, cams for respectively operating the same, actuating devices engaged with the 70 cams, and common means for holding the devices in engagement with the cams.

6. The combination with a stationary die and a slide coöperative therewith and adapted to bring successive blanks into 75 forcible contact therewith, of a stationary hopper, a sliding yoke mounted on said hopper, a detent carried by the yoke and adapted to enter said hopper, an abutment carried by the slide and for actuating said 80 detent to release a blank from the hopper, and independent means for moving said yoke in the opposite direction.

7. The combination with a die, a slide coöperative with said die and for bringing 85 successive blanks into forcible contact therewith, of means for supplying ink to said die, a blank-hopper, a yoke shiftable on said hopper and operable in opposite directions by said slide and inking mechanism respectively.

8. The combination with a die, a slide coöperative with said die and for bringing successive blanks into forcible contact therewith, a blank hopper, a yoke mounted for 95 movement on said hopper in opposite directions, a detent carried by the yoke, means carried by said slide for shifting said yoke in one direction, a carriage for supplying ink to said die, and means controlled by the 100 movement of said carriage and for shifting said yoke in the opposite direction.

9. The combination with a die having a flat face, a slide coöperative therewith and having a flat face, means for actuating said 105 slide and for rolling a blank into forcible contact with said die face, a carriage for supplying ink to said die, a blank-hopper, and means operable by said slide and said carriage respectively for releasing and holding the blanks in the hopper, and means for actuating said carriage.

10. The combination with a marking device, of a platen and inking mechanism alternately movable over the marking device, cams for respectively operating the same, levers respectively connected with the platen and inking mechanism and having bearings against the cams, and a spring interposed between and operating against the 115 levers for holding them in co-action with their respective cams.

11. The combination with a blank holder, of a feed controlling device coöperating therewith, a marking device, means for moving the blank against the marking device and separate movable inking mechanism for the marking device constituting actuating means for the feed controlling device.

12. The combination with a die and means 130

for supplying ink or similar material thereto, of a reciprocatory slide for bringing successive blanks into forcible contact with said die, a roller fixed against movement 5 with and disposed in the path of movement of the slide to clean the rolling surface of said slide, and resilient means for bringing said roller into contact therewith.

13. In a machine for printing round objects, as pencils, the combination with a flat bed, a die or type form fixedly supported in said bed, of a slide movable over and away from over said type form and at a higher level therefrom, and comprising upper and 15 lower sections, the lower one of which is yieldable relatively to the upper one, means for moving said slide, and means for successively bringing the round objects to be printed to the conjoint action of the said 20 type form and slide.

14. In a machine of the character described, the combination with a flat bed, and a die or type form adjustably and fixedly supported in said bed, of a slide movable 25 over and away from over said type form

and at a higher level therefrom, and comprising upper and lower sections, studs, carried by one of the sections, having guiding and limiting engagements with the other section, springs in compression between the 30 sections, and means for successively feeding the round articles to the conjoint action of said slide and type form.

15. The combination with a blank holder, of a feed controlling device coöperating 35 therewith for delivering blanks one at a time from the holder, a marking device, means for moving the blanks over the marking device, movable inking mechanism separate from said moving means, and an actuating lever for the feed controlling device located in the path of movement of and operated by the inking mechanism.

Signed by me at Brandon, Vt., in presence of two subscribing witnesses.

WILLIAM H. JOHNSON.
